TRANSPORTABLE LIFTING DEVICE

Nils Eric Nilsson, Mockeln, Sweden

Application January 20, 1950, Serial No. 139,601
In Sweden November 11, 1946

3 Claims. (Cl. 254—139)

1

The present invention relates to a transportable lifting device of the type having a frame supporting a rotatable cable drum for a cable passed over a return pulley, said frame consisting of a standard which may be placed with one end on the ground in unstable upright position and which has a handle by means of which said standard may be braced with one hand during the lifting operation.

The principal object of the invention is to provide a special embodiment of such known lifting devices which considerably facilitates the handling of the lifting device.

These and other objects and advantages of the invention will be clear from the following detailed description of an embodiment shown as an example only in the accompanying drawing in which:

Fig. 1 shows a side elevation of the lifting device, and

Fig. 2 a rear elevation thereof.

Referring to the drawing, the lifting device comprises a standard 1 which is constructed as a trestle with two tubular legs having an upper end 1a and a foot end 1b. The upper end 1a supports a return pulley 2 for a cable 3, the one free end of which supports a lifting means 4—shown here in the form of a pair of tongs for lifting logs 5—and the other end of which is wound around and attached to a cable drum 6 which is manually rotatable by means of a crank 7 for a customary gearing 8 with a latch pawl 9. The winch unit formed by the parts 6 to 9 is fixed approximately at the middle of the standard 1, and above said unit there is a handle 10 which the operator may grasp with one hand to hold the lifting device balanced in unstable upright position during use.

As appears from Fig. 1, the intermediate portion of the standard 1 is straight while the upper end 1a is bent towards the side remote from the winch unit 6 to 9 and the foot end 1b thereof is so bent in the same direction as the upper end 1a that the place where the standard stands on the ground (or other support), when the straight intermediate portion of the standard 1 is held vertical, is situated approximately directly below the return pulley 2. The arrangement is such that the axes of rotation of both the cable drum 6 and the return pulley 2 are at right angles to the plane of the bent standard ends 1a and 1b. As best shown in Fig. 2, the foot ends 1b of the tubular legs forming the standard 1 diverge slightly from each other in downward direction and are connected by means of a transverse bar 11 hav-

2

ing studs 12 which prevent slipping of the standard during use by engagement with the ground.

When using the device the lifting means 4 is secured to the part to be lifted (the log 5) and the device is erected directly adjacent the securing point. The operator grasps the handle 10 with his one hand and holds the device in upright position while turning the crank 7 with his other hand so that the cable lifts the log 5. Since in the embodiment described, the point where the foot end 1b is supported on the ground will be situated approximately in the prolongation of the portion of the cable 3 extending between the return pulley 2 and the lifting means 4 a very small force will be necessary to hold the device in upright position by means of the handle 10 and in spite thereof there is no risk that the log 5 will slide against and possibly come into contact with and get caught on the standard 1 during lifting.

What I claim and desire to secure by Letters Patent is:

1. A transportable lifting device comprising a standard, a straight cross bar on the foot end of said standard, a handle on said standard adapted for enabling an operator to brace said standard with one hand during use in unstable upright position with said cross bar on the foot end of said standard resting on a support and allowing swinging movements of said standard around said cross bar, the upper end and the foot end of said standard being bent in the same direction from a substantially straight intermediate portion of said standard in a plane at right angles to said cross bar, a cable drum mounted for rotation on said intermediate portion of said standard with its axis of rotation at right angles to the plane of said bent standard ends, a return pulley mounted for rotation on said upper standard end with its axis of rotation at right angles to the plane of said bent standard ends, a cable having one end thereof attached to said cable drum and the other end thereof being passed over said return pulley, and a manually operable crank for rotating said drum, the axis of rotation of said crank extending at right angles to the plane of said bent standard ends.

2. A transportable lifting device comprising a standard, a straight cross bar on the foot end of said standard, a handle on said standard adapted for enabling an operator to brace said standard with one hand during use in unstable upright position with said cross bar on the foot end of said standard resting on a support and allowing swinging movements of said standard around

said cross bar, the upper end and the foot end of said standard being bent in the same direction from a substantially straight intermediate portion of said standard in a plane at right angles to said cross bar, a cable drum mounted for rotation on the side of said intermediate standard portion remote from said standard ends with its axis of rotation at right angles to the plane of said bent standard ends, a return pulley mounted for rotation on said upper standard end with its axis of rotation at right angles to the plane of said bent standard ends, a cable having one end thereof attached to said cable drum and the other end thereof being passed over said return pulley, and a manually operable crank for rotating said drum, the axis of rotation of said crank extending at right angles to the plane of said bent standard ends.

3. A transportable lifting device comprising a standard, a straight cross bar on the foot end of said standard, a handle on said standard adapted for enabling an operator to brace said standard with one hand during use in unstable upright position with said cross bar on the foot end of said standard resting on a support and allowing swinging movements of said standard around said cross bar, the upper end and the foot end of said standard being bent in the same direction from a substantially straight intermediate portion of said standard in a plane at right angles to said

cross bar, a cable drum mounted for rotation on said intermediate portion of said standard with its axis of rotation at right angles to the plane of said bent standard ends, a return pulley mounted for rotation on said upper standard end with its axis of rotation at right angles to the plane of said bent standard ends, a cable having one end thereof attached to said cable drum and the other end thereof being passed over said return pulley, said cross bar being situated on the same side of a plane that is parallel with said intermediate standard portion and touches said return pulley on the side remote from said intermediate standard portion, and a manually operable crank for rotating said drum, the axis of rotation of said crank extending at right angles to the plane of said bent standard ends.
